SPARK PLUG

Hector Rabezzana, Flint, Mich., assignor, by
mesne assignments, to General Motors Corpora-
tion, Detroit, Mich., a corporation of Dela-
ware

Application October 2, 1933, Serial No. 691,763

4 Claims. (Cl. 123—169)

My invention relates to spark plugs for internal combustion engines of the type having a central electrode which extends through a passage provided in a porcelain or equivalent ceramic material insulator, and which insulator is secured in

5 place within a metallic outer shell or casing having a second electrode arranged in sparking relation to the inner end of said central electrode; and the object of my invention is to provide certain improvements in and relating to the central electrode structure and its relation to the insulating member whereby the latter is less likely to be broken or otherwise injured during the assembling of the central electrode therewith, and 10 the securing it in place in the passage aforesaid, and is subjected to less strain and possible injury when the plug is in use than has heretofore commonly been the case in spark plug insulators.

A further object of my invention is to provide 20 a spark plug with insulating member and central electrode features whereby such expansion of the electrode as occurs when the plug is in use, due to the heating thereof by burning gases within the engine cylinder, will be less likely to injure the insulating member as by cracking the same, or by 25 setting up stresses therein tending to crack or otherwise injure it, than has heretofore been the case in spark plugs; and a still further object of my invention is to provide central electrode and 30 insulating member features whereby heat communicated to the electrode by the burning gases will be more rapidly and effectively conducted to the insulating member and to the shell of the plug and the surrounding atmosphere than has heretofore commonly been the case.

With the above and other objects of invention in view my invention consists in the improved central electrode and insulating member features illustrated in the accompanying drawing, described in the following specification, and particularly claimed at the end thereof; and in such variations and modifications thereof, within the scope of the concluding claims, as will be obvious 45 to those skilled in the art to which my invention relates.

In the drawing wherein the preferred form of my invention is illustrated:

Figure 1 is a view showing a section upon a 50 longitudinally extending central plane, of a spark plug having electrode and insulating member features in accordance with my invention.

Figure 2 is a similar view showing slight variations of various of the features of my invention.

55 Figure 3 is a fragmentary sectional view upon

a transverse plane indicated by the line 3—3, Figure 2, upon a larger scale.

Figure 4 is a sectional view similar to Figures 1 and 2, but showing a modified form of my invention.

Figure 5 is a view showing the central part of the central electrode of Figure 4 in elevation and upon a larger scale.

Referring to the drawing, the reference numeral 10 designates the external metallic shell of a spark plug, which as usual is threaded to screw into a similarly threaded opening in an internal combustion engine cylinder head; and within this shell or casing is an insulating member 11, the same being shown as of the type having an enlarged central portion resting upon a ledge 12 of the casing, and as secured within the same by an inwardly bent holding flange 13. My invention, however, is not limited to any particular form of insulating member, nor to the scheme illustrated 20 for securing the same within the external shell of the plug.

The insulating member has a longitudinally extending passage extending through it, the same being of lesser diameter at its lower part 14 than at its upper part 15, whereby an internal supporting ledge 16 is provided; said ledge being preferably located within the enlarged central portion of the insulating member. The central electrode has a larger outer or upper part 17 extending 30 through the passage 15, a smaller inner and lower part 18 which extends through the passage 14, and an intermediate shoulder 19 which engages the ledge 16 when the central electrode is assembled with the insulating member.

The central electrode is a unitary single piece structure although it is commonly made in two parts joined together adjacent the shoulder 19, because the inner part is commonly made of a more expensive metal (in order to endure the high temperature met with when the plug is in use) than is necessary in the outer part, which is less highly heated and is not subjected to the action of the spark gap. The inner part 18 extends loosely through the passage 14 (that is, it is not cemented in place therein) so that the same may expand independently of the insulating member and without subjecting the latter to strain tending to break it, as the two are heated when the plug is in use. The outer end 17, however, is cemented in place within the passage 15 to secure the requisite gas-tight and non-leaking qualities necessary in a spark plug. The central electrode fits quite loosely within the passages through which it extends so that it may be readily put in

place without binding in the passages provided for it, so that the insulating member will not be broken or strained during the assembling of the parts; the requisite gas tightness of the plug being secured by cement which fills the interstices between the parts as next appears.

The upper part 17 of the central electrode is of hollow tubular form, as shown, and holes 20 are provided adjacent the lower end of this part and above the ledge 16 and shoulder 19 through which cement 21 (which is supplied under pressure through the electrode passage) may flow therethrough and through the holes and fill the interstices between said upper part and the interior 15 of the passage 15 through which it extends.

In Figure 1 the interior of the passage 15 is threaded as is likewise the upper end of the part 17 of the electrode, the threads thus providing roughness to secure a more firm holding action 20 of the cement 21. In all forms the threaded part which is above the upper extremity of the insulating member provides for holding nuts or other forms of terminal connector, for securing a supply conductor the plug, as will be understood.

In the form of my invention illustrated in Figure 2 the threads upon the upper electrode part 17 are large enough in diameter to engage loosely with the threads within the passage 15, so as to provide positive locking of the electrode in place 25 within the insulator passage, and the interstices between the parts are filled with cement as in the Figure 1 form to secure gas tight sealing about the electrode. In the form illustrated in Figure 1 the lower portion 18 of the central electrode is welded to the upper part at 22, whereas in the form illustrated in Figure 2 the two parts are secured together by forcing portions of the wall of the upper part, at its lower end, into holding engagement with the upper end of the lower part 30 18, as in the familiar "staking" method, and as shown at 23.

In the form of my invention illustrated in Figures 4 and 5 lugs 24 are formed at the lower end of the upper part of the central electrode by swaging, or equivalent forming process, and these engage loosely with a coarse internal thread 25 within and at the lower end of the larger outer passage 15 in the insulating member 11; the interstices between the parts being filled with cement as in the other forms described. This permits a rapid assembling of the central electrode preliminarily to the cementing step; and the location of the interlocking elements close to the ledge 16 and shoulder 19 provides a structure 40 wherein the engaging parts (the coarsely threaded part and the part having the lugs 24) being short, differential expansion of the metallic electrode and the insulating member will have little or no effect as regards loosening of the joint between the two.

The threaded parts of the forms illustrated in Figures 1 and 2 may likewise be adjacent the lower ends of the central electrode and the inner ends of the larger outer passages in the insulating member, with the same result in reducing the lengths of the interlocking engagement between the insulating member and the electrode to a minimum and thus avoiding entirely, or substantially so, the loosening effect of differential expansion when the plug becomes heated; and in all forms of my invention the filling of the space between the central electrode and the passage above the ledge 16 and shoulder 19 through which it ex-

tends provide for a rapid flow of heat from the central electrode to the insulating member and to the surrounding atmosphere.

Having thus described and explained my invention I claim and desire to secure by Letters Patent:

1. In a spark plug, an insulating member having an internal ledge intermediate its ends, a passage leading from said ledge to the inner end of said insulating member, and a larger passage 10 leading from said ledge to the outer end of said insulating member; and an electrode extending through both said passages and having a shoulder which rests upon the ledge aforesaid, and the upper part only of which electrode is cemented 15 in place within the larger passage in said insulating member; the upper part of said electrode being tubular in form, and smaller than the passage through which it extends, and the wall thereof of having a hole adjacent its lower end. 20

2. In a spark plug, an insulating member having an internal ledge intermediate its ends, a passage leading from said ledge to the inner end of said insulating member, and a larger passage leading from said ledge to the outer end of said 25 insulating member; an electrode extending through both said passages and having a shoulder which rests upon the ledge aforesaid, the upper part of said electrode being tubular in form, and smaller than the passage through which it extends, and the wall thereof having a hole adjacent said ledge and said shoulder; interlocking elements upon said electrode and within the larger passage aforesaid for holding said electrode in place within the passages through which it extends; and cement filling the interstices between the upper part of said electrode and the larger upper passage within which it lies. 30

3. In a spark plug, an insulating member having an internal ledge intermediate its ends, a 40 passage leading from said ledge to the inner end of said insulating member, and a larger passage leading from said ledge to the outer end of said insulating member; and an electrode extending through both said passages and having a shoulder 45 which rests upon the ledge aforesaid, and the upper part only of which electrode is cemented in place within the larger passage in said insulating member; the upper part of said electrode being tubular in form, and smaller than the passage 50 through which it extends, and the wall thereof having a hole adjacent said ledge and said shoulder. 55

4. In a spark plug, an insulating member having an internal ledge intermediate its ends, a 60 passage leading from said ledge to the inner end of said insulating member, and a larger passage leading from said ledge to the outer end of said insulating member; an electrode extending through both said passages and having a shoulder 65 which rests upon said ledge, and the upper part only of which electrode is cemented in place within the larger of the passages aforesaid, the upper part of said electrode being tubular in form and smaller than the passage through which it extends and the wall thereof having a hole adjacent its lower end; and interlocking elements upon said electrode and within the larger passage aforesaid, said elements being located adjacent the lower ends of said larger passage and 70 the upper tubular part of said electrode. 75

HECTOR RABEZZANA.
